UNITED STATES PATENT OFFICE.

ANTON WANIELISTA AND MARCIN OSTROWIECKI, OF CHICAGO, ILLINOIS.

WALL-PAPERING MACHINE.

1,327,127.

Specification of Letters Patent.

Patented Jan. 6, 1920.

Application filed March 28, 1919. Serial No. 285,920.

To all whom it may concern:

Be it known that we, ANTON WANIELISTA and MARCIN OSTROWIECKI, citizens of Poland, residing at Chicago, in the county of Cook and State of Illinois, have invented certain new and useful Improvements in Wall-Papering Machines, of which the following is a specification.

The primary object of the invention is to provide a machine serviceable in hanging wall paper and being designed for pasting and cutting strips of wall paper in suitable lengths for applying to the wall, it being possible to operate the paste-applying and the cutting mechanism at a distance from the machine.

A further object of the invention is to provide a machine through which wall paper is readily passed, the paper being cut into suitable strips for hanging with the edges thereof trimmed off if desired and with a coating of paste applied to the wall-contacting face or side of the paper.

A still further object of the invention is the provision of a machine adapted for passing wall paper therethrough for simultaneously trimming the longitudinal edges thereof and supplying paste to one side of the paper, the paper being automatically severed in strips of suitable length when desired, provision being made for regulating the amount of paste applied to the paper, all parts of the machine being easily accessible when desired.

With these general objects in view the invention will now be fully described in connection with the accompanying drawings in which like reference characters designate corresponding parts throughout the several views.

In the drawings,

Figure 1 is a top plan view of the invention, a portion thereof being indicated by dotted lines in its open position,

Fig. 2 is a side elevation thereof,

Fig. 3 is a longitudinal vertical sectional view of the same,

Fig. 4 is a front elevation of the invention partially broken away and

Fig. 5 is a view similar to Fig. 3 of a forward portion of the machine, illustrating the manner of severing the wall paper into strips.

Our wall papering machine comprises opposite sides 10 and 11 having curved forward and rear ends and connected together

in parallel relations by spacing rods 12 adjacent the opposite ends of the machine. A paste-applying roller 13 is journaled substantially centrally between the sides 10 and 11 adapted for turning in a paste-containing receptacle 14.

The receptacle 14 is provided with a transverse rod 15 at its rear end having curved extensions 16 slidably projecting through horizontal slots 17 in the side walls 10 and 11. Inwardly projecting clips 18 carried by the intermediate cut-away portions 19 of the sides 10 and 11 are positioned beneath the receptacle 14 for supporting the same and permitting longitudinal adjustment. An adjusting nut 20 upon threaded portions 21 of the extensions 16 is positioned between a pair of legs 22 at the opposite sides of the machine through which said extensions 21 freely extend and whereby the receptacle 14 is moved longitudinally relatively of the roller 13 by turning the nuts 20.

The rear edge or rim 23 of the receptacle 14 constitutes a scraper adjustable relatively of the roller 13 for removing any surplus paste as well as regulating the amount of paste carried by the roller out of the receptacle 14. Wall paper 24 is mounted upon a roller 25 journaled in inclined slots 26 in the sides 10 and 11 adjacent the rear end of the machine and above a transverse plate 27 secured between the said sides.

Rectangular panels 10' and 11' are cut out of the opposite sides 10 and 11 respectively, connected together by a rod 12' adjacent the top of the machine as well as by idler rollers 28 and 29.

The panel 10' is connected by hinges 30 with the side 10 so that the panels 10' and 11' with the rod 12' and the rollers 28 and 29 may be swung back to their open position when desired away from the roller 13 as illustrated by dotted lines in Fig. 1 of the drawings. Pinions 31 upon the axles of the rollers 28 and 29 outwardly of the panel 11' are adapted to mesh with a gear 32 upon the adjacent end of the roller 13 when the panels 10', 11' are normally positioned upon the sides 10 and 11 with the rollers 28 and 29 slightly spaced from the opposite sides of the roller 13. A latch 33 normally maintains the panels closed when the machine is positioned for operation. It will be understood that the paper 24 is passed from the roller 25 over the roller 13 when the panels 10' and 11' are open and upon being closed,

the rollers 28 and 29 engage the upper ornamental side of the paper 24 while the lower plain side thereof is engaged by the roller 13. Paste herein illustrated at 34 is provided in the receptacle 14 and it will be understood that by pulling upon the forward end of the paper 24 that the plain side thereof will receive a coating of the paste 34 by the action of the roller 13.

10 A shaft 35 is journaled between the sides 10 and 11 forwardly and above the level of the receptacle 14 having two arms 36 adjustably mounted thereon and adapted to be secured at desirable distances apart by means 15 of set screws 37 carried by said arms engaging the shaft 35. A paper-cutting wheel 38 is journaled in each of the arms 36 adapted for bearing upon the roller 28 directly beneath the axis thereof above the receptacle 14. Helical springs 39 having their inner ends secured to the shaft 35 encircling the opposite end portions of the shaft are anchored as at 40 to the adjacent sides of the machine. The springs 39 resiliently maintain 25 the cutters 38 engaging the paper 24 as it passes beneath the forward roller 28, thereby trimming either or both of the longitudinal edges of the paper 24, the cutting operation being readily adjusted by shifting 30 the arms 36 upon the shaft 35 as well as adjusting the tension of the springs 39 by turning the shaft 35 in the arms 36 and then securing the screws 37. The machine simultaneously trims the paper 14 and applies paste 35 thereto while being pulled longitudinally through the machine.

A stub axle 41 is provided outwardly of each of the sides 10 and 11 slightly forwardly of the plane of the roller 28 having 40 a grooved bed-plate 42 mounted thereon by means of posts 43 with said bed-plate positioned above the sides of the machine. A serrated knife 44 is carried between arms 45 journaled upon the stub axles 41 between the 45 post 43 and adjacent the sides of the machine, the knife 44 being adapted to move upwardly for reception within the bed 42 for severing the paper 24 transversely at the upper forward part of the machine.

50 Arcuate strips 46 substantially concentric with the axles 41 connect the posts 43 and arms 45 together, the springs 46 being normally tensioned when the knife 44 is in its lowered position out of contact with the bed 42 as herein illustrated in the drawings. A swinging latch 47 carried by one of the posts 43 has a pin 48 adapted to seat within a notch 49 of the adjacent arm 45 for retaining the arms 45 and knife 44 in their open 55 set positions.

A pull cord 50 is attached to the free end of the latch 47 and it will be seen that the workman mounted upon a ladder may carry the free end of the paper upwardly of the 65 wall to be covered and when the proper

length of paper has been drawn through the machine and covered with paste by the roller 13, a pull upon the cord 50 releases the latch 47, permitting the springs 46 to operate the knife 44 severing the paper 24.

Upon releasing the latch 33, the panels 10', 11' may be turned back and the paper 24 with its holder 25 readily removed from the machine and a new supply inserted therein if desired. After severing one 75 length of the paper 24, the free end thereof will fall upon the shaft 35 and may be readily grasped for pulling an additional length or strip of paper through the machine, the upper side of the paper 24 being unaffected by the paste 34, the paper may be drawn rearwardly over the upper rod 12' for positioning upon a table with the paste side up if so desired. The machine may be employed for repeated operations rendering 80 the preparation of wall paper for hanging less laborious and more quickly accomplished.

What we claim as new is:—

1. A machine comprising sides, a paste-applying roller journaled therebetween, a receptacle beneath the roller longitudinally adjustable relatively of the roller, a scraper on one end of the receptacle adjacent the roller, idler rollers movably journaled at opposite sides of the paste roller and means carried by said sides adapted for holding wall-paper for passing through the machine above the paste roller and beneath said idler rollers.

2. A machine comprising sides, a paste roller journaled therebetween, a paste receptacle slidably mounted between said sides with said roller positioned therein, a scraper on one end of the receptacle adjacent said roller, adjusting means for the receptacle outwardly of said sides, and means adapted for guiding paper through the machine in contact with said roller.

3. A machine comprising sides, a paste roller journaled therebetween, a paste receptacle slidably mounted between said sides with said roller positioned therein, a scraper on one end of the receptacle adjacent said roller, adjusting means for the receptacle outwardly of said sides, panels in said sides connected together adapted for swinging movement laterally of the machine, spaced idler rollers journaled between said panels positioned at opposite sides of the paste 110 roller when the panels are in their normal closed positions and mounting means for wall paper rearwardly of said rollers adapted for supplying paper longitudinally through the machine above said paste roller 115 and beneath said idler rollers.

4. A machine comprising sides, a paste roller journaled therebetween, a paste receptacle slidably mounted between said sides with said roller positioned therein, a scraper 120

- on one end of the receptacle adjacent said roller, adjusting means for the receptacle outwardly of said sides, panels in said sides connected together adapted for swinging 5 movement laterally of the machine, spaced idler rollers journaled between said panels positioned at opposite sides of the paste roller when the panels are in their normal closed positions, mounting means for wall paper 10 rearwardly of said rollers adapted for supplying paper longitudinally through the machine above said paste roller and beneath said idler rollers, spaced controlling wheels for the paper adjustably resiliently engaging 15 beneath the forward one of said idler rollers and transverse cutting means at the forward end of the machine adapted for severing wall paper subsequent to the trimming and paste-applying operation.
- 20 5. A papering machine comprising sides, paste-applying means between said sides adapted for coating wall paper passing longitudinally through the machine between said sides, trimming wheels for the paper 25 during its movement through the machine and transverse spring actuated severing means for the paper adapted for automatic
- operation when released and releasing means for the knife adapted for actuation at a distance from the machine adjacent the forward end of the paper being operated upon. 30
6. A papering machine comprising sides, paste-applying means between said sides including guide rollers, means rearwardly of said rollers adapted for supplying wall paper 35 for passage longitudinally through the machine in engagement with said rollers, adjustably tensioned and adjustably spaced trimming means for the paper normally engaging one of said rollers, severing means 40 for the wall paper at the forward end of the machine, an operating spring for said severing means, a latch adapted for holding said severing means in set position and a cord attached to said latch adapted for releasing 45 the latch whereby the severing means automatically engages the pasted and trimmed paper after leaving the forward end of the machine.

In testimony whereof we affix our signatures.

ANTON WANIELISTA.
MARCIN OSTROWIECKI.
